UNITED STATES PATENT OFFICE.

JOSEPH S. OECHSLE, OF PHILADELPHIA, PENNSYLVANIA, ASSIGNOR TO METAL-WELD SERVICE CORPORATION, OF PHILADELPHIA, PENNSYLVANIA, A CORPORATION OF PENNSYLVANIA.

WELDER'S TONGS.

Application filed September 12, 1923. Serial No. 662,246.

To all whom it may concern:

Be it known that I, JOSEPH S. OECHSLE, a citizen of the United States, residing at Philadelphia, in the county of Philadelphia and State of Pennsylvania, have invented a new and useful Welder's Tongs, of which the following is a specification.

This invention relates to tools used in connection with electric arc welding in which one electrode is the material to be cut, welded or repaired, and the other electrode is the cutting, welding or repair material; and it has more particular reference to welder's tongs and devices having ability 15 to grip different sizes of electrodes.

More specifically this invention has reference to welder's tongs having insulated handle portions and clamping jaws adapted to grip an electrode, and means whereby an 20 electric conductor is detachably connected to the handle portions.

The primary object of my invention is to provide a welder's tongs of the type referred to having a better means for connecting the positive electric wire to the lower half or handle end of said tongs. In practice I have found that in order to obtain the highest possible amount of current at the 25 extreme upper or jaw end of the tongs it is necessary and essential to have a joint between the electric wire and tongs capable of efficiently carrying the heavy current used. As a result, another object of my present invention is to give a very high conductivity to the tongs in order to prevent 30 heating up of the handle portions.

With the foregoing and other objects in view which will be hereafter referred to, or become apparent to those conversant with 40 the art, my invention consists in the novel features of construction, combination and arrangement of parts hereinafter fully described, and more specifically defined by the subjoined claims.

In the further disclosure of the invention reference will be made to the accompanying sheet of drawings, constituting a part of this specification, and in which, like characters of reference designate the same or 45 corresponding parts in all the views.

Figure 1 is a side elevation of my novel welder's tong with the split ends of an electrical conductor connected thereto.

Figure 2 is a sectional plan taken substan-

55 fially on the line 2-2 in the preceding figure, and as viewed in the direction of the arrows thereon.

Figure 3 is a transverse section on the line 3-3 in Figure 2; and

Figure 4 is an end elevation of the tool, 60 as viewed from the right hand of Figure 1, with the electrical conductor removed.

Referring more particularly to the drawings, my novel welder's tongs comprises opposed metal members 5, 6 of high electrical 65 conductivity, one of said members being provided with integral ears 7, 7 between which is freely fitted an integral lug 8 on the opposed member 6, pivotal connection being established between said parts by a 70 pin 9 passed through registering holes in said ears and lugs. It will, of course, be clear that the pin 9 is made a friction fit in either the ears 7, 7 or lug 8, so as to permit free rocking of the members 5, 6 relative to each other. The aforesaid assemblage thus provides handle portions and jaws for the tool or tongs, and I find it preferable to fashion one of the jaws with serrations or teeth 10 for more efficiently gripping the 80 electrode not shown.

As an insulating and protective agent, I fit each aforesaid members 5, 6 with a semi-circular section fiber hand-grip 11, conveniently secured thereto by countersunk screws 85 12 in the well known way. In order to provide proper grippage for the tongs I fit a strong V-shaped flat spring 13 between the handle portions or members 5, 6 the same seating in longitudinal recessions 14 provided for the purpose therein, and as will be clearly apparent to those acquainted with the art.

Each of the aforesaid members 5, 6 is formed at its outer end, remote from the 95 jaw portions proper, with an integral bifurcated or slotted extension lug 15, and it is to be particularly noted that said lugs 15 are reversely disposed with respect to each other, so that their slots 16 register 100 in a common plane, or are in direct alignment, as will be best seen from Figure 4, wherein I have indicated a common center line 17 to specially emphasize this feature, the purpose and object whereof will be hereafter more fully set forth. The bifurcated or slotted extension lugs 15 form female 105 high electrical conductive joints for the ter-

2

terminal or male ends 18 of the current conductor 19, it being of course understood that said current conductor is split to provide portions 20, 20 which are appropriately secured into the cupped parts 21 of said terminal ends 18. These terminal ends 18 are made a friction fit into the bifurcated or slotted lugs 15, and they are detachably connected thereto by bolts 22 in the well known way. It is here worthy of particular note that by forming the parts 15, 18 as just described, although the bolts 22 may work loose, the efficiency of the tool will not diminish, neither will there be any drop in voltage, due to the fact that the bearing surface or connection to the tool is made a friction fit on both sides. This feature I deem of prime importance, as it effectively ensures the conduction of full current at all times even though the aforesaid bolts 22 should become loosened from some unforeseen or accidental cause.

Furthermore, it is also to be remarked that the slotted lugs or extensions 15 are disposed at right angles to the electrode gripping faces or jaws, so that as the handles or grips 11, 11 are closed and opened the conductor connections 20, 20 will be attached at an angle that ensures the least possible relative movement, whereby breakage strains at their point of connection to the parts 31, is reduced to a minimum.

From the foregoing description and an examination of the drawings, it will be perfectly clear to anyone acquainted with the art, that by my invention I have greatly increased the efficiency of welder's tongs in a simple, economical and satisfactory manner. Incidentally, the countersinks for the heads of the screws 12 are filled in with an appropriate insulation whereby the operator is protected from any danger of shock. Still further, I desire to state in conclusion, that I lay no claim whatsoever broadly to the production of a new form of welder's tongs, per se, but that I have by my novel method

of attaching the electrical conductor, greatly increased the efficiency and utility of such implements. Furthermore, by making the metal parts of material having a maximum degree of electrical conductivity, and connecting the conductor to the tool in the manner, and by the means shown and described, I have made a meritorious advance in the art. 55

Having described my invention what I claim as new and desire to secure by Letters Patent, is:

1. In a welder's tongs comprising body members of high electrical conductivity the combination of means for detachably connecting an electric conductor thereto, said means embracing bifurcated extension lugs integral with the body members, cupped terminals adapted to receive the split end of the electrical conductor and having flattened portions frictionally fitting into the aforesaid bifurcated extension lugs, said extension lugs being reversely disposed relative to each other at right angles to the plane of the tongs jaws with the cupped conductor receiving parts in a common operative plane, and means detachably connecting the lugs and flattened terminal portions together. 70

2. In a welder's tongs comprising opposed and pivotally connected members of high electrical conductivity, hand grips of fiber secured to said members, and a V-shaped flat spring seating between the aforesaid members to ensure proper grippage for the jaws, the combination of bifurcated extension lugs integral with the pivoted members remote from the gripping jaws, said lugs being disposed in planes at right angles to said jaws, electrical conductor terminals having flattened portions frictionally fitting into the bifurcated lugs, and means detachably connecting the aforesaid lugs and flattened terminal portions together. 85

In testimony whereof, I affix my signature this 4th day of September, 1923.

JOSEPH S. OECHSLE.
